HEEL BUILDING MACHINE

John A. McMahon and Ernest Sydow, St. Louis,
Mo., assignors to John E. Mitchell Company,
Dallas, Tex., a corporation of Missouri

Application December 1, 1941, Serial No. 421,108

21 Claims. (Cl. 12—50)

The general object of this invention is to provide a novel heel building machine which in design and operation will enable various types and characters of heels to be built thereon which, in ordinary practice, would require the use of four different machines. Thus at the present time, in the same factory, there may be found in operation a whole lift machine, a randing machine, a machine for building leather or combination heels of all types for women's shoes, and a rubber heel spotting machine; that is, a machine for applying rubber heels to heel blanks. Some of these machines are capable of use in more than one capacity. For example, a heel blank consisting of a whole lift and a half lift, or of a whole lift and a whole rand, can be built either on the whole lift machine or on the randing machine; a heel blank consisting of a whole lift, a half lift and a half rand, or of a half lift and a three-piece lift, can be built on the randing machine; a woman's decked heel, composed of whole lifts and wedge lifts can be built on the whole lift machine or on the machine designed especially for building heels for women's shoes. But whole lift heels for men's shoes are only built on the whole lift machine, and heel blanks consisting of a leather base and rubber heel are only built on the rubber heel spotting machine.

Now a machine constructed according to our invention will enable all the types of heels, or heel blanks, referred to, to be built thereon, requiring, in some cases, momentary adjustment for height, and in others, slight re-arrangement of the heel forming mechanism, according to the size, shape, or style of heel being built, both of which can be readily and expeditiously made, and the means for permitting these changes in the set-up of the machine being an important part of the invention.

The machine, as to its dominant features, is characterized by an endless conveyor composed of a relatively large number of pivotally connected clamp carriers; novel heel forming mechanism; an adjustable clamping plate on each clamp carrier; heel discharging mechanism, and retracting mechanism for the heel forming and heel discharging mechanisms; and a plurality of mechanisms placed in sequential operation by a single action of the operator, preferably by depressing a foot treadle, and operating automatically to move the heel former inward to a position to cause a built-up heel-blank to be placed on a clamp carrier at the completion of each stage of movement of the conveyor; to force the clamping plate into clamping engagement with

the heel-blank; to return the heel former to its original position; to unclamp a finished heel-blank, discharge it from the machine, and return the discharging device to its original position; and finally, to impart a single stage movement to the conveyor to bring to rest an empty clamp carrier opposite the heel former, i. e., in position to have a freshly built heel-blank positioned thereon.

10 Embodied in the machine is a main drive shaft provided with a clutch operated by the foot treadle, and a cam shaft having a number of cams thereon which actuate most of the mechanisms above referred to, and which is rotated 15 through a single cycle from the main drive shaft each time the treadle is momentarily depressed to close the clutch.

The power for causing the travel of the endless conveyor in the embodiment of the invention herein shown, is derived from coil springs, which are extended and then allowed to contract in each actuation of the treadle. It is within the contemplation of the invention, however, to actuate the endless conveyor at will 25 from the main drive shaft in a manner similar to that in which the cam shaft is rotated from the drive shaft; that is, by the use of conventional clutch mechanism.

In the accompanying drawings—

30 Fig. 1 is a plan view of a machine constructed according to our invention, the containers, or bins, for the lifts to be pasted, assembled and clamped being omitted for clearness of illustration;

35 Fig. 2 is a view in front elevation of the machine;

Fig. 3 is a view in rear elevation of the same; Fig. 4 is a view in end elevation, viewed from the left-hand end of the machine;

40 Fig. 5 is a similar view, looking toward the right-hand end of the machine;

Fig. 6 is a broken cross-section, taken on the line 6—6 of Fig. 3;

45 Fig. 7 is a similar view, taken on the line 7—7 of Fig. 3;

Fig. 8 is a similar view, taken on the line 8—8 of Fig. 3;

50 Fig. 9 is a similar view, taken on the line 9—9 of Fig. 3;

Fig. 10 is a similar view taken on the line 10—10 of Fig. 3;

Fig. 11 is a fragmentary sectional view taken on the line 11—11 of Fig. 1;

Fig. 12 is a broken plan view of the operating

mechanism shown at the left of Fig. 1, showing the stop mechanism in a released position;

Fig. 13 is an enlarged view, partly in section, of the clamp adjusting gauge shown in Figs. 2 and 3;

Fig. 14 is a broken sectional enlargement of the clutch mechanism shown in Fig. 7;

Fig. 15 is a plan view of the same;

Fig. 16 is a sectional view taken on the line 16—16 of Fig. 14;

Fig. 17 is a view in front elevation on an enlarged scale of the heel-building and delivering mechanism, the clamping mechanism appearing at the rear being broken off;

Fig. 18 is a sectional plan view taken on the staggered line 18—18 of Figs. 17 and 20;

Fig. 19 is a horizontal section taken on the staggered line 19—19 of Figs. 17 and 20;

Fig. 20 is a vertical sectional view taken on the line 20—20 of Fig. 17, the heel-building mechanism, or heel former, being in its normal, or outward, position;

Fig. 21 is a horizontal section taken on the staggered line 21—21 of Figs. 17 and 20;

Fig. 22 is a view similar to Fig. 20, the heel former being shown in its inward, or delivering, position, and the operating parts in the position to which they have been moved for clamping the heel-blank;

Fig. 23 is a view in front elevation, on an enlarged scale, of one of the heel-blank clamping members and carriers, of which, in the present machine, forty-two are employed, as shown by Fig. 1; these clamp carriers are connected together and each is provided with wheels to enable it to travel over rails, a portion of one of which is shown in the figure; as is also a clamped heel-blank;

Fig. 24 is a view in side elevation of a clamp carrier and clamped heel-blank, the supporting rails being shown in section;

Fig. 25 is a vertical sectional view taken on the line 25—25 of Fig. 23;

Fig. 26 is a horizontal sectional view taken on the line 26—26 of Fig. 23, and which, in effect, is a plan view of one of the clamping plates;

Fig. 27 is a broken vertical sectional view on an enlarged scale, taken on the staggered line 27—27 of Fig. 23;

Fig. 28 is a horizontal section on the line 28—28 of Fig. 23;

Fig. 29 is a similar section on the line 29—29 of Fig. 23;

Fig. 30 is a detached sectional view on the line 30—30 of Fig. 24;

Fig. 31 is a view in front elevation on an enlarged scale of one of the heel-blank clamps and carriers, with a heel-blank clamped therein, as it appears upon arrival at the discharge station, the figure being, in effect, a section taken on the line 31—31 of Fig. 33;

Fig. 32 is a vertical sectional view taken on the line 32—32 of Fig. 31;

Fig. 33 is a horizontal section taken on the line 33—33 of Fig. 31;

Fig. 34 is a view in sectional elevation taken on the line 34—34 of Fig. 32;

Fig. 35 is a view similar to Fig. 32, but showing the clamping plate raised and a heel discharged by an ejecting device; and

Fig. 36 is a fragmentary plan view, partly in section, of the heel forming and guiding mechanism.

Referring now to the drawings, and particularly to Figures 1 to 5 thereof, the numeral 1

indicates the front supporting standards, and 2 the rear supporting standards of the frame of the machine, which frame is substantially rectangular in shape. Connecting these standards 3 at opposite ends of the frame are frame bars 3, 3, Fig. 4, and 4, 4, Fig. 5. Mounted in bearings on the rear standards 2 is the main drive shaft 5, on one end of which is secured a pulley 6 which is driven by a belt 7 from a source of power (not shown). Beside pulley 6 is mounted on the shaft a loose pulley 8, a belt shifter 9 being employed to shift the belt from one pulley to the other, according to whether the machine is to be driven, or its motion stopped. Mounted on the drive shaft 5 near its opposite end is a clutch 10 (Fig. 3) comprising a loose clutch member 11 (Fig. 6) and a fast clutch member 12 (Fig. 7). The numeral 13 (Fig. 2) indicates a foot treadle, to be actuated at will by an operator, which is secured at its inner end on a rock-shaft 14 pivotally supported in hangars 15 depending from a cross-beam 16 secured at its ends to, and extending between, the front standards 1 of the frame. Also secured on rock-shaft 14 adjacent the head of the treadle is a rocker-arm 17, extending downward from the rock-shaft, and pivotally connected at its lower end to one end of a connecting bar 18, the other end of which is secured to a depending rocker-arm 19, the upper end of which is secured to a rock-shaft 20, supported in bearings 21 on the lower frame bars 3 and 4, as shown more clearly in Figs. 4 and 6. The lower end of rocker arm 19 is pivotally connected to one end of a connecting bar 22, the other end of which is pivotally connected to the lower end of a rocker-arm 23, which depends from and is integral with a circular cam member 24 (Figs. 3 and 6), the outer face of which is provided with cam surfaces 25 working against complementary cam surfaces on a fixed cam member 26 mounted on the frame of the machine. The cam member 24 is loosely mounted on the drive shaft 5 and abuts against the hub 27 of a sprocket gear 28, said hub and gear being loose on shaft 5. When the treadle 13 is depressed, the connecting bar 18 is moved to the rear, moving the rocker arm 19, connecting bar 22 and rocker-arm 23 in the same direction. This movement causes the cam member 24 to be rotated and the cam surfaces 25 to ride over the complementary cam surfaces on the fixed cam member 26, thereby moving its hub 27 into engagement with the side of the sprocket gear 28 and moving the latter inward, or toward the right in Fig. 3, causing the loose clutch member 11 to be moved into frictional engagement with the fast clutch member 12, which is constantly rotated by the drive shaft 5. The loose clutch member 11 and the sprocket gear 28 have a common hub 29, so that when the loose clutch member is rotated by engagement with the fast clutch member 12 the sprocket gear 28 will be caused to be rotated. Secured on a cross-shaft 30 (Figs. 5 and 6), supported in bearings 30a mounted on the lower frame bars 3 and 4, is a sprocket gear 31, considerably larger in diameter than the sprocket gear 28, and which is operatively connected to the latter by means of a sprocket chain 32. Secured on the inner side of the sprocket 31 is a small sprocket wheel 33 (Fig. 7). Located above the cross-shaft 30 and rotatably mounted in bearings 34a (Fig. 10) in the side frame members of the machine, is a cam shaft 34 on which is loosely mounted a relatively large sprocket wheel 35 which is operatively connected to the sprocket

wheel 33 by a sprocket chain 36. Mounted on this cam shaft 34 are a number of cams to be later described, and which are brought into operation in a given order, so that when the cam shaft is rotated the various operations of the machine will be caused to occur in a given sequence, as will later appear. The numeral 37 (Fig. 6) indicates a coil spring, one end of which is secured to the rock-shaft 14 and the other to the rocker-arm 19. In the operation of the machine, the treadle 13 is held in a depressed position only momentarily, and when released, the spring 37, which had been placed under tension when the treadle was depressed, operates to return the treadle and the cam faces 25 to normal position, thereby permitting the loose clutch member 11 to separate from the fast clutch member 12. The return movement of the treadle 13 is arrested by an adjustable stop screw 38 (Fig. 6), which is adapted to be engaged by the lower end of rocker-arm 19. The fixed clutch member 26 may be secured in adjusted positions by means of a simple clamp 33 (Fig. 3).

Referring briefly to Figs. 17, 20, 22 and 36, the heel lifts 40 are first pasted and then assembled on a base plate 41 with their breast ends inserted between two sets of heel forming plates 42, 42, mounted in superimposed relation in holders 43 and clamped thereto by means of set screws 44.

In building up a heel-blank according to the present invention, the lifts are assembled in order from the bottom, or tread portion, to the upper portion, or base, of the heel. To avoid confusion, it should be stated that the smallest lift, or that at the bottom of the heel when the latter is secured on the shoe, is referred to in the art as the "top" lift, owing to the fact that ordinarily heel-blanks are built up from the largest portion of the heel to the smallest, or tread portion, which becomes the upper end of the heel as it is built, and hence the last and smallest lift secured on the heel is referred to as the top lift.

To enable the heel-blanks to be built up in the manner herein shown and described, each of the heel forming plates 42 (Fig. 36) is provided on its inner end with a portion 42a which serves as a breast plate, and with inward-extending projections 45 which diverge from each other in an upward direction to form a space corresponding to the shape of the heel at the sides of the breast. Each of the plates 42 is approximately the thickness of an average heel lift, the two series of projections 45 thus forming stepped recesses for receiving the lifts in order from the smallest to the largest lift employed in building the heel blank. The holders 43 are mounted on the inner end of a movable support 46 which is mounted to slide in guides 46a over the top of the base plate 41. The support 46 carrying the holders 43 with the heel forming plates 42 clamped thereto will hereinafter be referred to as the heel former. After a heel-blank has been assembled on the base plate 41, the first operation that occurs upon depressing treadle 13 is the movement of this heel former inward to carry the assembled heel-blank into position on a travelling heel clamp carrier 47 (Fig. 22), and the mechanism for effecting this operation will now be described.

Secured on the cam shaft 34 (Fig. 9) is a cam 48 having a cam groove 49 formed in one face thereof. Pivoted at its lower end on the shaft 34 is an actuating lever 50, the upper end of which is pivotally connected at 51 to the inner end of a connecting rod 52, the other end of

which is pivotally connected at 53 (Fig. 22) to the lower end of a crank-arm 54, the upper end of which is secured on a rock-shaft 55 mounted in bearings 55a at the front of the machine. A second crank-arm 54b is similarly secured on rock-shaft 55 and its upper end is pivotally connected to one end of a link 56, the other end of which link is pivotally connected to a lug 57 carried by, and projecting downward from the bottom of the support 46. As the cam shaft 34 is rotated through the medium of sprocket 35 and sprocket chain 36 from the sprocket 33, as previously described, the cam 48 will be turned. Mounted on the actuating lever 50 is a roller 58 which engages in the cam groove 49, and as the high part of this cam groove passes over the roller 58 the actuating lever 50 will be moved toward the front of the machine, thereby partially rotating rock-shaft 55 and moving the crank-arms 54 and 54b from the position shown in Fig. 20 to that shown in Fig. 22, and thus moving a heel former inward and moving the heel-blank from the base plate 41 onto the bottom of the clamp carrier 47. In the continued revolution of cam 48, the low part of cam groove 49 will engage roller 58 and return the heel former to the normal position shown in Fig. 20. The next operation that occurs is the clamping of the heel-blank deposited as described above on the clamp carrier 47; and this operation will now be described, referring, first, particularly to Figs. 7 and 8.

Pivotedly mounted on a cross-shaft 59 located at the rear part of the machine is a lever arm 60 which extends well toward the front of the machine and at its inner end is bifurcated, as indicated in Figs. 1, 18, 19 and 21, the two arms 61 of this bifurcated end being connected, respectively, at 62 to the upper ends of two links 63 located on opposite sides of a slide bar, or plunger, 64 (Fig. 20), and being connected at their lower ends to a cross-pin 65 passing through said bar. The plunger 64 is slidably mounted in bearings 66 mounted on the frame of the machine. Secured on the cam shaft 34 is a cam 67, the peripheral face of which normally engages a wear plate 68 secured on the under side of the lever arm 60. As the cam 67 rotates, its high point passing under and in engagement with wear plate 68 raises the inner end of lever arm 60 which in turn, through links 63, raises the plunger 64, which operates to actuate the clamping mechanism, illustrated in Figs. 17 to 35, and which will now be described.

The numeral 69 (Figs. 20 and 22) indicates a rack-bar which is slidably mounted for vertical movement in guides 70 secured on the frame of the machine, and the teeth of which are in mesh with a spur gear 71 rotatably mounted in fixed bearings 72 on the frame. The numeral 73 indicates a companion parallel rack-bar, also slidably mounted for vertical movement in frame guide members 74, and the teeth of which are in mesh with the teeth of spur gear 71 on the side opposite that engaged by the teeth of rack-bar 69. Projecting outwardly from the central portion of rack-bar 69 is an integral boss 75, which is internally screw-threaded to receive a screw-threaded rod 76, which is located above and in line with the slide bar 64. The screw-threaded rod 76 is vertically adjustable, for a purpose later explained, but its normal position may be assumed to be that shown by Fig. 20.

Each of the heel clamp carriers previously referred to is provided on its under side with rollers

77, shown on an enlarged scale in Figs. 23 to 25, which run on tracks 78 supported on the frame of the machine, and which extend entirely around the machine, as shown by Figs. 1 and 2. Each of the clamp carriers 47 is provided at one corner on its inner side with a pair of apertured lugs 79 (Fig. 1) which are circular in shape, and which receive between them an apertured lug on the corner of an adjacent carrier, the interlocking lugs receiving a pivot pin 80, all of the carriers thus connected forming an endless-chain conveyor. Slidably mounted in the sides of each clamp carrier are two parallel bars 81, which are connected at their upper ends by a cross-bar 82 and at their lower ends by a cross-bar 83 (Figs. 23, 24 and 31), thus providing a slidable clamping frame. Secured at their upper ends in, and projecting well below the under side of each carrier 47, are two parallel rods 84, which are connected at their lower ends by a cross-bar 85. Formed integral with the cross-bar 83 at each end thereof, respectively, are two sleeves 86 which are slidably mounted on the rods 84. Loosely mounted in the cross-bar 82 of each carrier is a pin 87, the head 87^a of which engages the upper side of the cross-bar 82, and acts as a stop, or retaining member. Pivottally mounted at 88 in a boss 89 on the lower end of pin 87 is an adjustable clamp plate 90; and a coil spring 91, surrounding the pin, is interposed between boss 89 and the under side of cross-bar 82. The clamp plate 90 is illustrated in Figs. 26 and 27, and may be briefly described as comprising the pivoted plate itself, which is yieldingly held in the inclined position shown by means of a small coil spring 92 interposed between the boss 89 and an abutment at the breast end of the plate, permitting the plate to accommodate itself to various inclinations at the base of decked heels, as shown particularly in Figs. 24, 25 and 32. Also, pivotally mounted on the pivot 88, in a rectangular recess 93 provided in plate 90, is an independently-movable plate 94, normally held flush with the face of the clamp plate by means of a leaf spring 95. When the clamp plate is forced downward into engagement with the base of a heel-blank, indicated in the views where shown by the letter H, plate 94 will be enabled to engage the hollowed out portion of the base at the breast of the heel to afford a firm engagement of the clamp plate with the base of the heel, as illustrated in Fig. 27. In such position, the breast end of the plate 94 will project a greater or less distance below the face of the clamp plate 90, depending upon the extent to which the base lift has been gouged out. If a heel-blank with a perfectly flat base is clamped, as in heels for men's shoes, plate 94 will remain flush with the face of the clamp plate. This type of pressure plate is fully described and claimed in the patent to Dennis Parks, No. 2,176,560, dated October 17, 1939. For lowering and raising the clamp plate 90, the following mechanism is provided.

Secured at its upper end in a boss 96 on the under side of the clamp carrier 47 is a rack-bar 97 (Figs. 22, 25, 31, 32 and 35) which at its lower end is secured in the cross-bar 85, centrally thereof. Projecting downward from the central portion of the cross-bar 83 are two parallel arms 98 (Fig. 30) between which is rotatably mounted a pinion 99 on a cross-pin 100. Pivotally mounted between arms 98 at their lower ends is a ratchet 101 which normally engages the teeth of pinion 99 and is yieldingly held in such engagement by downward pressure of a coil spring 102 mounted

in a housing 103 provided on cross-bar 83 and engaging a tail piece 104 on said ratchet.

Assuming the operator has built up a heel-blank on base plate 41, he depresses foot treadle 13, and through the mechanism previously described, and shown particularly in Figs. 3 and 6, forces the loose clutch member 11 into engagement with the fast clutch member 12 which, through the sprocket and chain driving mechanism also previously described, places cam shaft 34 in rotation. Cam 48 on said shaft (Fig. 9) now operates to move the heel former from the position shown in Fig. 20 to that shown in Fig. 22 and deposit the heel-blank on clamp carrier 47. Cam 67 (Fig. 8) now operates to raise the outer end of lever arm 68, which by means of links 63 raises plunger 64 until its upper end engages the lower end of screw-threaded rod 76 and raises it, and with it the rack-bar 69 by reason of the engagement of the screw-threaded rod with lug 75 on the rack-bar. As the latter moves upward, it causes spur gear 71 to be rotated counterclockwise and thus move rack-bar 73 in a downward direction. Projecting outward from the upper end of this rack-bar is an arm 105 which extends over the cross-bar 83 and normally at some distance above the same, as shown by Fig. 20, and in the downward movement of rack-bar 69 engages said cross-bar and through the medium of slidably mounted bars 81 draws cross-bar 82 downward to carry the clamp plate 90 into engagement with the upper side of the heel-blank (Figs. 23-25), and then to place spring 91 under tension to cause it to exert the proper pressure on the clamp plate. Ratchet 101, which rode over the teeth of pinion 99 as the latter was rotated by engagement with the teeth of rack-bar 97 in the downward movement of the clamping frame, now engages behind a tooth of the pinion and prevents the latter from being rotated in the opposite direction and thus securely locks the clamp in its clamped position. Just prior to the descent of the clamping plate on the heel-blank, the low part of cam 48 will pass over roller 58 and cause the heel former to be returned to the position shown in Fig. 20. As each heel-blank is clamped it is moved forward, in the operation of the machine, a distance sufficient to bring an empty clamp carrier opposite the base plate 41, while at substantially the same time a clamped heel-blank, which has travelled around the entire machine in order to give the paste between the lifts time to set, and arrived at a discharge point, or chute, 106 (Fig. 1), will be released and ejected from its clamp carrier immediately beyond the empty carrier moved into position, the clamp carrier from which the heel has been discharged becoming the empty carrier next to receive a heel-blank.

All the operations of the machine occur in stages, and while the clutch members 11 and 12 are momentarily held in engagement by depression of treadle 13. However, the time interval between the various operations is very slight, depending upon the setting of the cams on the cam shaft, and in some instances, as in the clamping of a fresh heel-blank and the discharge of a completed heel, the two actions occur almost simultaneously. The mechanisms for effecting the travel in stages of the endless series of connected clamp carriers, the release of the clamp of a completed heel arriving opposite the chute 106, and the ejection of such heel from its carrier will next be described in order.

Referring to Fig. 1, the machine is provided at opposite ends with two upright stub shafts indi-

cated, respectively, by the numerals 107 and 108, and rotatably mounted on these shafts are two large sprocket wheels 109 and 109^a which are provided in their peripheries with equidistant recesses 110 adapted to receive the lugs 79 on the corners of the clamp carriers 47, which thus acts as an endless-chain carrier, or conveyor. Fixedly secured to the hub of each of the wheels 109, 109^a, is a ratchet wheel 111, shown more clearly in Fig. 12, from each of which projects a crank-arm 112, the outer ends of these crank-arms being connected to opposite ends of a connecting rod 113, which is provided near the sprocket wheel 109 on its outer side with a cam surface 114. Mounted on each of the arms 112 is a ratchet 115, which is mounted in keepers 116, and yieldingly held in engagement with the teeth of the ratchet wheel 111 by a coil spring 117. Projecting inward from connecting rod 113, near its left-hand end as shown in Fig. 1, is an arm 118 to which are secured the ends of two coil springs 119, the opposite ends of which are secured to a fixed arm 120 extending inward from a longitudinal frame member 121. Pivotally mounted on the frame member 121 is a stop-arm 122 provided on its outer end with a roller 123 which is normally pressed toward the periphery of wheel 109 by means of a spring 124 (Fig. 12). Normally, roller 123 rests in one or the other of the recesses 110 of wheel 109, which position it is caused to take, as later explained, to stop the rotation of the wheel, and hence the movement of the endless series of clamp carriers. Rotatably mounted in a bracket 125 on the under side of stop-arm 122 is a roller 126 which normally engages the upper side of connecting rod 113 beyond the cam surface 114, and is adapted to be engaged by said cam surface to raise stop-arm 122 and release roller 123 from engagement with a recess 110 to permit wheel 109 to be rotated. The means for effecting a partial rotation of wheel 109 and causing a single rotation of cam shaft 34 when the foot treadle 13 is depressed, will now be described. Secured on the rock-shaft 20, previously referred to is a second rocker-arm, 127 (Fig. 7) extending inward from the rock-shaft in an upwardly-inclined direction, and pivotally mounted at its lower end about centrally of this rocker-arm, as indicated at 128, is an upright arm 129, which near its upper end is provided with a shoulder 130 (Fig. 14) which normally engages under a lug 131 (Fig. 15) provided at the outer end of a clutch-control bar 132 pivotally mounted at its inner end at 133 on a front frame member of the machine. The arm 129 is normally held with its shoulder under lug 131 by means of a coil spring 134 secured at its upper end to the inner side of said arm and at its lower end to the outer end of rocker arm 127. The sprocket gear 37 previously referred to is provided on one side with a hub 135, provided around its periphery with a plurality (usually three) of lateral recesses 136 (Figs. 15 and 16), each of which is provided with an inclined edge 137 to facilitate the entrance into the recess of a rectangular clutch pin 138 which is slidably mounted in a clutch ring 139 secured on the cam shaft 34 and having a hub 140 provided with an open peripheral recess 141 which is adapted to slidably receive the inner end of clutch pin 138. The inner end portion of this clutch pin is provided on its outer side (the upper side as shown in Fig. 15) with a transverse recess 142 provided at one end and on one side with an inclined surface 143. The lug 131 is formed with a rectangular projection 144 adapted to engage in the recess 75

142, said projection having a downwardly inclined projection 145 having an inclined side 146 designed to cooperate with the inclined surface 143 of the clutch pin. The clutch pin 138 is normally held in a retracted position, or that shown in Fig. 15, by engagement of the projection 144 in its recess 142. In this position, one side of the inner end of the clutch pin will have engaged a shoulder 147 on lug 131 to arrest further movement of the clutch ring. A coil spring 148 (Fig. 16) housed in a recess in the inner end portion of the clutch pin, and held under tension by a keeper 149 secured on the inner end of hub 140, operates to force the clutch pin into one or the other of the recesses 136 whenever the clutch control bar 132 is raised to release said clutch pin. Secured on the cam shaft 34 is a cam 150 (Fig. 10), and below this cam is a lever arm 151 which is pivotally mounted at its inner end at 151 on a front frame member of the machine. Mounted on the upper side of this lever arm is a wear plate 152 which, when the cam shaft 34 is rotated, will be engaged by the high portion of cam 150 and cause the outer end of lever arm 151 to be depressed. Pivotally connected at its lower end 153 to the outer end of lever arm 151 is a pull rod 154, which at its upper end is pivotally connected at 155 (Figs. 10 and 11) with one arm 156 of a bell-crank lever 157, pivotally mounted at its elbow at 158 on the lower end of a support 159 secured at its upper end to the frame of the machine. The other arm 160 is pivotally connected at its upper end to one end of a link 161, the other end of which is pivotally connected to a boss 162 secured on the connecting rod 113. It will now be seen that when foot treadle 13 is depressed to turn rock-shaft 20, rocker-arm 127 will cause upright arm 129 to be raised, and the engagement of its shoulder 130 with lug 131 will lift its projection 144 out of the recess 142 in the clutch pin and spring 148 will force said clutch pin outward against the face of hub 135 where it will enter one or the other of the recesses 136 as soon as it is rotated to a position opposite the end of the pin. Clutch ring 139 will now be placed in rotation thereby causing the rotation of cam shaft 34, during which rotation the clutch-control bar 132 will be held in an elevated position, as shown by dotted lines in Fig. 14. As the cam shaft rotates, the high point of cam 150 will engage wear plate 152 and force the outer end of lever arm 151 downward, causing pull rod 154 to turn bell-crank lever 157 to the left (Fig. 11), and moving connecting rod 113 in the same direction, or from the position shown in Fig. 1 to that shown in Fig. 12. In this movement of the connecting rod ratchets 115 will be moved by crank arms 112 over the teeth of ratchet wheels 111 and finally engage behind one of said teeth, as shown as to one of said ratchets in Fig. 12. This movement of connecting rod 113 toward the left, as shown in Fig. 1, places coil springs 119 under tension by stretching, or extending, them, and at the same time causes cam surface 114 thereon to ride under roller 125 (Fig. 12) and raise stop-arm 122, disengaging its roller 123 from engagement with a recess 110 in sprocket wheel 109. When the low point of cam 150 (Fig. 10) reaches wear plate 152, the power stored in springs 119 by the previous movement will be exerted to move connecting rod 113 to the right, thereby, through the ratchet mechanism described, turning the wheels 109 and 109^a clockwise and causing the movement in the same direction of the endless series of clamp carriers.

The movement to the right of connecting rod 113 also acts to release stop-arm 122, which is forced downward by its spring to enable its roller 123 to engage in a recess 110 in sprocket wheel 109 succeeding that in which it had previously rested, and thus stop the rotation of the sprocket wheels and thus stop the rotation of the endless carrier. In addition to the positive stop of sprocket wheel 109 just described, it is desirable, also, to arrest the rotation of shaft 30 at the same time. To this end we provide the brake mechanism shown in Figs. 8, 9 and 10. Secured on shaft 30 is a brake drum 163, surrounding the upper side of which is a brake band 164 anchored at one end on a bolt 165 mounted in a plate 166 secured on the frame, and having its other end bent at an angle and apertured to loosely receive a rod 167 having a nut 168 on its upper end, between which and the apertured end of the brake band is confined a coil spring 169. A nut 170 is mounted on rod 167 below the apertured end of the brake band to hold it in position on the rod. The lower end of rod 167 is connected to the outer end of a short rocker-arm 171 secured on a rock-shaft 20. When the treadle 13 is depressed to turn rock-shaft 20, and through the mechanism which has been described to cause cam shaft 34 to be rotated, the rocker-arm 171 will raise pin 167 and release pressure of spring 169 on the brake band and also slightly raise the end of the latter, permitting free rotation of shaft 30. When the operator releases pressure on the foot treadle, spring 31 (Fig. 6) turns the rock-shaft and the rocker-arm 171 back to normal position, and the brake band is applied to the brake drum 163 under pressure of spring 169. The automatic release of the clutch pin 138 from a recess 136 in the hub of sprocket gear 35 is effected in the following manner:

The clutch-control bar 132 (Fig. 7) is always subject to the downward pull of a coil spring 172, which is secured at its upper end in said bar and at its lower end to a lug 173, which is conveniently loosely mounted on rock-shaft 20. The cam ring 139 (Fig. 14) is provided in its periphery with a curved cam groove 174, shown by dotted lines, and on one side of the upright arm 129 there is rotatably mounted at 175 a roller 176, also shown by dotted lines. When the cam ring is locked to the sprocket gear 35 by clutch pin 138 and placed in rotation, the cam groove acting on roller 176 forces the upper end of arm 129 outward and moves shoulder 130 from under lug 131, permitting clutch-control bar to fall so that its projecting portion 144, 145, will rest on the periphery of hub 140. As the cam ring 139 nears the completion of its revolution, the inclined projection 145 will engage the inclined surface 143 of the clutch pin and force its withdrawal from the recess 136 in which it was engaged, thereby opening the clutch, and the inner end of the clutch pin will engage shoulder 147 on lug 131 and stop further rotation of the cam ring. At the same time with the above operations, cam groove 174 will pass under roller 176 and permit spring 134 to draw arm 129 inward to bring its shoulder 130 under lug 131.

The movement and stoppage of the endless carrier above described will have brought a clamped and dried heel blank to rest opposite the opening to the chute 106 (Figs. 1 and 2), where it is to be discharged. The operations of unclamping the heel blank and effecting its discharge will now be described.

Referring to Figs. 33 to 35, inclusive, the numerals 177, 177^a, indicate two parallel rack-bars which are mounted for vertical movement in guides 178 connected at top and bottom, as indicated at 179, to constitute a guide frame, which is bolted at its upper and lower ends to angle irons 180 on the frame of the machine. The numeral 181 indicates a shaft rotatably mounted in bearings 182 on the guide frame, on each end of which is secured a pinion 183, 184, respectively, which pinions are in mesh with the rack-bars 177, 177^a. The purpose of these pinions is to transmit motion from the rack-bar 177^a to the rack-bar 177. Secured on the rack-bar 177 is a contact member 185 having a vertical arm 186 and a horizontal arm 187, the latter being located under the ratchet 101, and the vertical arm 186 under the tail piece 104 of said ratchet. Secured on the lower end of the rack-bar 177^a is a bracket 188 to which is pivotally connected the lower end of a link 139, the upper end of which is pivotally connected to the outer end of a lever arm 190 (Fig. 6), which is pivotally mounted on the cross-shaft 59 previously referred to. Secured on the under side of lever arm 190 is a wear plate 191, which normally rests upon the low point of a cam 192 secured on crank-shaft 34. Adjacent the cam 192, and conveniently formed integral with its hub 193, is a smaller and more abrupt-acting cam 194. Loosely mounted at its lower end on shaft 30 is a lever arm 195, the upper end of which is pivotally connected at 196 to a push-rod 197, which is pivotally connected at 198 to the rear end of a slide-bar 199, operating in a grooved guide member 200 mounted on the frame of the machine (Fig. 34). The slide-bar 199 is provided at its forward end with an ejector 201. Lever arm 195 is provided on its inner side with a wear plate 202 for contact by cam 194, which is normally held in engagement with said cam, or its hub, by means of a coil spring 203 (Figs. 1 and 6) secured at one end to the upper end of arm 195 and its other end to the frame member 121.

When cam shaft 34 is placed in operation, and a finished heel blank is brought to rest opposite the chute 106, cam 192 (Fig. 6) will have been turned to raise the outer end of lever arm 190 and thereby raise rack-bar 177^a (Fig. 35) through pinions 184 and 185 raising rack-bar 177. In this movement, contact arm 186 will engage the tail piece 104 of ratchet 101 and release it from engagement with pinion 99, after which contact arm 187 will engage the lower ends of arms 83, between which the pinion is mounted, and raise cross-bar 83 and, through bars 81 and cross-bar 82, clamp plate 90, as will be readily apparent by comparing Fig. 32 with Fig. 35. Almost simultaneously with the above action, the high point of cam 194 (Fig. 6) acts on lever arm 195 to rapidly move the push rod 197 forward, and the ejector 201 engages the heel blank and discharges it into chute 106.

Referring particularly to Figs. 23 and 31, there is secured at each end on the front side of cross-bar 83 a friction spring 204, which in its central portion bears against the rear side of rack-bar 97 and frictionally holds the clamping frame and clamp plate 90 in the extreme upward position shown in Fig. 35 until arm 105 again engages the upper side of cross-bar 83 (Figs. 20 and 22) and again forces the clamp plate 90 into engagement with a freshly built heel blank. When, in the continued rotation of cam shaft 34 cam 194 (Fig. 6) passes out of engagement with the wear

plate 232 on lever arm 105, the spring 253 returns push-rod 167 to normal position, or that shown in said figure. We will now describe the method of building heel blanks and maintaining the pasted lifts in their proper assembled position while being clamped and during a portion of the movement of the endless carrier, first premising that the particular mechanism involved is embodied in a separate application for patent.

Referring to Figs. 1 and 2, there is mounted on a support, or table, 205 at the front of the machine a paste applying device 206 of any preferred construction, but as here shown comprising a lower roller 207 and an upper roller 208 between which the lifts are passed to receive paste in a well known manner. The lower roller rotates in a paste pot 209, and supplies paste to the upper roller, the paste being maintained in a fluid condition by an electric heater (not shown) supplied with current by a conductor 210. The roller 207 is rotated by a shaft 211 (Fig. 6) having a pulley 212 driven by a belt 213 from a pulley 214 (Fig. 3) on drive shaft 5. As each lift is passed between the rollers of the paste applying device to be supplied with paste, it is positioned with its breast against the heel-forming plates 42 and its sides against the respective projections 45, and when the required number of lifts have been superimposed one upon the other to form the heel-blank, the latter is ready to be moved onto a clamp carrier to be clamped by the plate 90, as previously described.

Referring now to Figs. 1 and 36, a series of heel-engaging back-bars 215 are shown mounted in superimposed relation immediately behind the line followed in their movement by the inner, or rounded, sides of the heel-blanks as they are moved beyond (to the left of) the heel former 43 by the travelling clamp carriers 41. Each of these bars is provided on its inner side with two arms 216 which are inserted in keepers 217 and secured in position by clamp screws 218. Like the heel-forming plates 42, these back-bars are approximately the thickness of an average heel lift, and they are positioned in stepped relation to conform exactly to the incline of the rounded side of a decked heel-blank. When the heel-blank is moved inward by the heel former to be clamped, the lifts at its rounded side will engage the stepped back-bars 215 and will be held from displacement when clamped. As shown by the drawings, one end of the assembled back-bars is directly opposite the heel former, and the freshly clamped heel-blank will slide along the back-bars as its clamps carrier is moved in stages beyond its position opposite the heel former. As shown by Fig. 1, the back-bars are long enough to engage four heel-blanks at one time, so that four separate movements of the endless carrier will occur before a freshly-clamped heel-blank is moved beyond, and out of engagement with, the back-bars. This gives the paste between the lifts time to partially set, so that there is no danger of the lifts becoming displaced under the clamping pressure as the heel-blank is carried around the machine to the discharge point.

For minimizing the jar to the machine occasioned by the stoppage of sprocket wheel 103 when one of its recesses 110 is engaged by stop-arm 122, we provide the dash pot arrangement shown in Figs. 1 and 12. The numeral 219 indicates a cylinder pivotally connected at its inner end to the frame of the machine, in which

works a piston having a piston rod 220 projecting from its outer end. This end of the piston rod is pivotally connected to one end of a lever 221, which at its other end is pivotally connected 5 to the frame member 121 as indicated at 222. Pivotally connected at one end to the lever 221 toward its inner end is an arm 223, the other end of which is pivotally connected to the connecting rod 113, as indicated at 224. It is obvious that when the connecting rod 113 is moved to the left, in Fig. 1, as previously described, the piston rod 220 will be drawn out of the cylinder, and when said connecting rod is moved to the right by springs 119, the air will be compressed 10 in cylinder 219, thereby absorbing the shock of the engagement between stop-arm 122 and a recess 110.

We have heretofore referred to the fact that the screw-threaded rod 76 is adjustable, and this 15 feature will now be described, referring to Figs. 2, 3, 13, 20 and 22.

Extending upward from, and forming a continuation of the screw-threaded rod 76 is a plain rod 225 extending through a cylindrical guard 226 which at its lower end is connected to the upper end of rack-bar 69, as shown at 227, and at its upper end provides guide 228 for slidably receiving rod 225. Mounted on the upper end of rod 225 is a cylindrical head 229 having on its upper end a thumb screw 230. Secured at their 20 lower ends on the upper end of guard 226 are two parallel arms 231 provided with numbered graduations, and secured on head 229 is an indicator 232 having bifurcated ends sliding over the graduated arms 231. By turning thumb-screw 230 in one direction or the other, the screw-threaded rod 76, through its engagement in the screw-threaded boss 75, will be raised or lowered, as the case may be, thereby varying the distance 25 rack-bar 69 will be raised when the lower end of screw-threaded rod 76 is engaged by plunger 64, and consequently varying the distance rack-bar 73 carrying arm 105 will be moved downward. As the function of arm 105 is to move the clamp frame downward, it is obvious that the extent of the downward movement of clamp plate 90 may be regulated by the means described 30 according to the height of the heel-blanks being built. Such height being known, the thumb-screw 230 is turned to move indicator 232 to the corresponding graduation on the arms 231 so that the proper throw of clamp plate 90 will be secured.

For convenience of the operator, we mount 35 above the machine a bin 233 open at its front side and provided with a number of compartments 234 for holding lifts of the various sizes required for building a decked heel. This bin is mounted on columns 235 supported on the frame of the machine.

The organization, or set-up, of the machine herein shown and described is that employed for 40 building decked heels for ladies shoes. As indicated in the opening part of the specification, however, different set-ups of the machine may be provided for building various other types of heels. For example, in building flat heels, the back-bars 215 would be entirely dispensed with, and the heel-forming plates be reduced in number to, say, two or three, and the projections 45 arranged with their engaging faces flush with each other, and separated the proper distance apart according to the width of the lifts being employed. Similar adjustments would be made

when rubber heels were being cemented to the heel-blanks.

We wish it to be understood that the invention is not limited to the exact details of construction herein described and illustrated in the drawings, except as may be required by certain of the appended claims, and that various changes may be made in the construction, arrangement, organization and operation of the machine, or its elements, without departing from the spirit of the invention.

We claim:

1. A heel building machine comprising, in combination, an endless series of carriers mounted to travel around the machine and past a loading station and a discharge station, and each of which carriers has a clamp mounted thereon, a reciprocable heel former located at said loading station, a reciprocable ejector located at said discharge station, mechanism for operating said heel former to deposit a freshly built heel-blank on one of said carriers, mechanism for clamping said heel-blank, mechanism for causing a stage movement of the carriers to bring an empty one to rest at said loading station, and a carrier with a clamped heel-blank therein, which has travelled around the machine, to rest at said discharge station, mechanism for unclamping said heel-blank, and mechanism for operating said ejector to eject the heel-blank, a cam shaft adapted to be placed in rotation at the will of the operator, a series of cams thereon for operating said mechanisms in substantially the order named, and automatic means for arresting the rotation of said cam shaft at the end of a complete rotation thereof.

2. A heel building machine comprising, in combination, an endless conveyor consisting of a series of pivotally connected carriers each of which has a depressible clamping member mounted thereon, said conveyor being arranged to travel around the machine and past a loading station and a discharge station, a plurality of mechanisms operating, respectively, to deposit a freshly built heel-blank in one of said carriers, to clamp said heel-blank by depressing said clamping member, to cause a stage movement of the conveyor to bring an empty carrier to rest at the loading station, and a clamped heel-blank, that has been carried around the machine, to rest at the discharge station, to unclamp said heel-blank, and to eject the same from the machine, a main drive shaft having a clutch, a cam shaft, driving means including said clutch for rotating the cam shaft from the drive shaft, automatic stop mechanism for the cam shaft, an operator's treadle, means actuated by depressing said treadle for closing said clutch and simultaneously releasing said stop mechanism, whereby to permit rotation of said cam shaft, a series of cams on said cam shaft operating to actuate said plurality of mechanisms in substantially the order named, means operating on the release of said treadle to open said clutch, and automatic means operating to restore said stop mechanism to its stop position to arrest the rotation of the cam shaft at the end of a complete rotation thereof.

3. A heel building machine comprising, in combination, an endless conveyor consisting of a series of pivotally connected carriers each of which has a depressible clamping member mounted thereon, said carriers being arranged to travel around the machine and past a loading station and a discharge station, a plurality of mechanisms operating, respectively, to deposit

a freshly built heel-blank in one of said carriers, to clamp said heel-blank by depressing said clamping member, to cause a stage movement of the conveyor to bring an empty carrier to rest at the loading station, and a clamped heel-blank, that has been carried around the machine, to rest at the discharge station, to unclamp said heel-blank, and to eject the same from the machine, a main drive shaft having a clutch, a cam shaft having an automatic clutch, driving means including said clutches for rotating the cam shaft from the drive shaft, an operator's treadle, control means governing the opening and closing of said automatic clutch, means actuated by depressing said treadle for closing said clutch and simultaneously releasing said control means to permit the cam shaft clutch to close, thereby causing the cam shaft to be rotated, automatic means operating to restore said control means to a position to cause the cam shaft clutch to open, and a stop on said control means for arresting the rotation of the cam shaft at the end of a complete rotation thereof.

4. A heel building machine comprising, in combination, an endless conveyor consisting of a series of pivotally connected carriers each of which has a depressible clamping member mounted thereon, said carriers being arranged to travel around the machine and past a loading station and a discharge station, a plurality of mechanisms operating, respectively, to deposit a freshly built heel-blank in one of said carriers, to clamp said heel blank by depressing said clamping member, to cause a stage movement of the conveyor to bring an empty carrier to rest at the loading station, and a clamped heel-blank, that has been carried around the machine, to rest at the discharge station, to unclamp said heel-blank, and to eject the same from the machine, a main drive shaft having a clutch, a cam shaft having an automatic clutch, driving means including said clutches for rotating the cam shaft from the drive shaft, an operator's treadle, control means governing the opening and closing of said automatic clutch, means actuated by depressing said treadle for closing said clutch and simultaneously releasing said control means to permit the cam shaft clutch to close, thereby causing the cam shaft to be rotated, automatic means including a cam on said cam shaft operating to restore said control means to a position to cause the cam shaft clutch to open, and automatic stop mechanism for arresting the rotation of the cam shaft at the end of a complete rotation thereof.

5. A heel building machine comprising, in combination with the frame of the machine, a pair of relatively large, horizontally-disposed sprocket wheels mounted, respectively, at opposite ends of said frame, an endless conveyor operatively mounted on said sprocket wheels and consisting of a series of pivotally-connected traveling carriers each of which has clamping mechanism mounted thereon, a drive-shaft having a friction clutch, an operator's treadle, mechanism actuated thereby on depressing and releasing the treadle to close and open said clutch, and a plurality of automatic mechanisms, including a reciprocable heel former on which heel-blanks are built up, placed in actuation on closing said clutch for depositing a freshly built heel-blank in one of said carriers, for operating its clamping mechanism to clamp the heel-blank, for turning one of said sprocket wheels, thereby causing the travel of the conveyor, and for releasing

ing said clamping mechanism at a predetermined point distant from the heel former, in the travel of the conveyor, and automatic stop mechanism operating to lock said last-named sprocket wheel from rotation and stop the movement of said conveyor as each carrier in turn arrives at said predetermined point.

6. A heel building machine comprising, in combination, an endless conveyor consisting of a series of pivotally-connected carriers mounted to travel around the machine in a horizontal plane and past a loading station and a discharge station, a vertically movable normally upwardly urged clamping member mounted on each carrier, automatic mechanisms for causing the travel of said conveyor and for arresting its movement as successive carriers arrive opposite said loading and discharge stations, respectively, automatic mechanism for depressing a clamping member at said loading station, automatic means on said clamping member for locking it in its depressed position, automatic mechanism for releasing said locking mechanism and for raising said clamping member at said discharge station, driving means, and means for actuating said automatic mechanisms from said driving means at the will of the operator.

7. A heel building machine comprising, in combination, an endless conveyor consisting of a series of carriers mounted to travel in a horizontal plane around the machine and past a loading station and a discharge station, a vertically movable frame mounted on each carrier and provided with a rack-bar and with a pinion engaging the same, a ratchet engaging said pinion and locking it against rotation in an upward direction, a clamping plate mounted in each frame, driving means, and a plurality of automatic mechanisms placed in actuation from said driving means at the will of the operator for causing a stage movement of said conveyor to bring successive empty carriers to rest at the loading station to receive a freshly built heel-blank, and successive carriers having a clamped heel-blank therein to rest at the discharge station, for depressing the frame of the carrier at the loading station to cause its clamping plate to clamp the freshly built heel-blank and its pinion to travel downward over its rack-bar to be locked at the limit of its downward movement by the engagement of the ratchet with a tooth of said pinion, and for releasing the ratchet and raising said frame to unclamp the heel-blank at said discharge station.

8. A heel building machine comprising, in combination, an endless conveyor consisting of a series of carriers mounted to travel in a horizontal plane around the machine and past a loading station and a discharge station, a vertically movable frame mounted on each carrier and provided with a rack-bar and with a pinion engaging the same, a ratchet engaging said pinion and locking it against rotation in an upward direction, a clamping plate mounted in each frame, driving means, and a plurality of automatic mechanisms placed in actuation from said driving means at the will of the operator for causing a stage movement of said conveyor to bring successive empty carriers to rest at the loading station to receive a freshly built heel-blank, and successive carriers having a clamped heel-blank therein to rest at the discharge station, for depressing the frame of the carrier at the loading station to cause its clamping plate to clamp the freshly built heel-blank and its pinion to travel

downward over its rack-bar to be locked at the limit of its downward movement by the engagement of the ratchet with a tooth of said pinion, and a unitary device operated by the machine for releasing the ratchet and raising said frame to unclamp the heel-blank at said discharge station.

9. A heel building machine comprising, in combination, an endless conveyor consisting of a series of pivotally-connected carriers mounted to travel around the machine in a horizontal plane and past a loading station and a discharge station, a vertically movable clamping member mounted on each carrier, automatic mechanism for causing the travel of said conveyor and for arresting its movement as successive carriers arrive opposite said loading and discharge stations, respectively, automatic mechanism for depressing a clamping member located at said loading station, automatic mechanism for raising said clamping member located at the discharge station, automatic heel-ejecting mechanism operating at the discharge station, driving means, and means for actuating said automatic mechanisms from said driving means at the will of the operator and substantially in the order named.

10. A heel building machine comprising, in combination, an endless conveyor consisting of a series of pivotally-connected carriers mounted to travel around the machine in a horizontal plane and past a loading station and a discharge station, a vertically movable clamping member mounted on each carrier, automatic mechanism for causing the travel of said conveyor and for arresting its movement as successive carriers arrive opposite said loading and discharge stations, respectively, automatic mechanism for depressing a clamping member located at said loading station, automatic mechanism for raising said clamping member located at the discharge station, driving means, means for actuating said automatic mechanisms from said driving means at the will of the operator, and means for regulating the throw of said clamp-depressing mechanisms in accordance with the height of the heel-blank being clamped.

11. A heel building machine comprising, in combination with the frame of the machine, an endless runway mounted thereon and extending entirely around the machine, an endless series of pivotally-connected clamping members mounted to travel over said runway, depressing and releasing mechanisms for said clamping members located adjacent each other at one side of the machine, driving means, means under the control of the operator for causing a movement in stages of said clamping members to successively bring two clamping members to rest opposite said depressing and releasing mechanisms, respectively, and means placed in operation in initiating the travel of said clamping members for depressing one clamping member and releasing another clamping member after the latter has completed the circuit of the runway.

12. In a heel building machine of the class described, in which an endless series of carriers is caused to travel in stages around the machine to successively bring two carriers to rest at a loading station and a discharge station, respectively, a vertically movable clamping member mounted on each carrier, operating mechanism therefor, including a vertically adjustable rod, mounted on the machine at the loading station, a reciprocable plunger operated by the machine for engaging and raising said rod to cause a member of said operating mechanism to engage and de-

press the clamping member of a carrier at rest at said loading station, and means for adjusting said rod to vary the throw of the clamping members in accordance with the height of the heel-blanks to be clamped.

13. In a heel building machine of the class described, in which an endless series of carriers is caused to travel in stages around the machine to successively bring two carriers to rest at a loading station and a discharge station, respectively, a vertically movable clamping member mounted on each carrier, operating mechanism therefor mounted on the machine at the loading station, means operated by the machine to cause a member of said operating mechanism to engage and depress the clamping member of a carrier at rest at said loading station, means on each carrier for locking its clamping member in a depressed position, operating mechanism for the clamping members mounted on the machine at the discharge station, and means operated by the machine to cause said latter mechanism to release the locking means and raise the clamping member of a carrier at rest at said discharge station.

14. A clamp carrier for use in a machine of the character described comprising a wheeled base, a clamping-frame slidably mounted for vertical movement thereon, a clamping plate yieldably mounted in and depending from the top of said frame, a fixed rack-bar depending from said base, a pinion carried by the clamping-frame and meshing with the teeth of said rack-bar, and a ratchet associated with said pinion and operating to lock the same against rotation to prevent upward movement of said clamping-frame from a lowered position.

15. A clamp carrier for use in a machine of the class described comprising a base, a clamping-frame slidably mounted for vertical movement thereon, a clamping plate yieldably mounted in and depending from the top of said frame, and releasable locking means on said carrier operating to prevent upward movement of said clamping-frame from a lowered position.

16. In a heel building machine, a base, an endless series of carriers movable on the base to bring each carrier to a loading station, thence around the machine to a discharge station, and back to the loading station, clamping means on each carrier comprising clamping elements, one movable toward the other, means to dispose a plurality of cement containing, superposed lifts in the clamping means at the loading station, means to cause one clamping member to move toward the other to engage and hold the lifts together, means to displace the carrier one stage at a time toward the discharge station, while holding the clamping member in clamping relation, the staged movement bringing the carriers successively to loading and discharge stations, and means to release the clamping means at the discharge station whereby the now cemented heel blank may be ejected from the carrier.

17. In a heel building machine, a base, an endless series of carriers movable on the base to bring each carrier to a loading station, thence around the machine to a discharge station, and back to the loading station, clamping means on each carrier comprising clamping elements, one movable toward the other, means to dispose a plurality of cement containing, superposed lifts in the clamping means at the loading station, means to cause one clamping member to move toward the other to engage and hold the lifts

together, releasable latch means to hold the clamping means together, means to displace the carrier one stage at a time toward the discharge station, while holding the clamping member in clamping relation, the staged movement bringing the carriers successively to loading and discharge stations, and means to release the latch means at the discharge station, whereby the clamping means may release the now cemented heel blank and the same may be ejected from the carrier.

18. In a heel building machine, a base, an endless series of carriers movable on the base to bring each carrier to a loading station, thence around the machine to a discharge station, and back to the loading station, clamping means on each carrier comprising clamping elements, one movable toward the other, means to dispose a plurality of cement containing, superposed lifts in the clamping means at the loading station, means to cause one clamping member to move toward the other to engage and hold the lifts together, means to displace the carrier one stage at a time toward the discharge station, while holding the clamping member in clamping relation, the staged movement bringing the carriers successively to loading and discharge stations, and means to release the clamping means at the discharge station whereby the now cemented heel blank may be ejected from the carrier, and a plurality of cam mechanisms to operate the several means in the order named.

19. In a heel building machine, a base, an endless series of carriers movable on the base to bring each carrier to a loading station, thence around the machine to a discharge station, and back to the loading station, clamping means on each carrier comprising clamping elements, one movable toward the other, means to dispose a plurality of cement containing, superposed lifts in the clamping means at the loading station, means to cause one clamping member to move toward the other to engage and hold the lifts together, means to displace the carrier one stage at a time toward the discharge station, while holding the clamping member in clamping relation, the staged movement bringing the carriers successively to loading and discharge stations, and means to release the clamping means at the discharge station whereby the now cemented heel blank may be ejected from the carrier, and a plurality of cam mechanisms to operate the several means in the order named, with a one-cycle clutch adapted to operate the mechanism from the point at which the disposing means loads one carrier to the point at which it loads the next carrier.

20. In a heel building machine, a base, an endless series of carriers movable on the base, operating means to bring each carrier from a loading station around to a discharge station and back to the loading station, a clamping member on each carrier including two clamping elements movable one toward another, means at the loading station to move one of the clamping elements toward the other, and means to adjust the extent of movement of said last-named means to vary the extent of movement of said one clamping element toward the other.

21. In a heel building machine, a base, an endless series of carriers movable on the base, operating means to bring each carrier from a loading station around to a discharge station and back to the loading station, a clamping member on each carrier including two clamping elements movable

one toward another, means at the loading station to move one of the clamping elements toward the other, and means to adjust the extent of movement of said last-named means to vary the extent of movement of said one clamping element toward the other, said means comprising a reciprocable member, and a second member to be engaged by the reciprocable member and displaced upon reciprocation thereof, a clamp engaging

means, means connecting the second member to the clamp engaging means, and means to move the second member on the clamp engaging means and toward and from the reciprocable member to vary the movement of the second member and the clamp engaging means upon reciprocation of the reciprocable member.
